CLAIM

The ornamental design for a ball game component as shown and described.

DESCRIPTION

FIG. 1 is a first perspective view of a ball game component showing our new design;

FIG. 2 is a second perspective view thereof;

FIG. 3 is a front elevational view thereof, a rear elevational view thereof being a mirror image of the front elevational view;

FIG. 4 is a right-side elevational view thereof, a left-side elevational view thereof being a mirror image of the right-side elevational view;

FIG. 5 is a top plan view thereof; and,

(Continued)

FIG. 6 is a bottom plan view thereof.

Dash-dash broken lines in the figures illustrate portions of the ball game component that form no part of the claimed design. Dot-dash broken lines in the figures are boundary lines that illustrate boundaries of the claimed design and form no part of the claimed design.

1 Claim, 6 Drawing Sheets
